Patented May 2, 1961

190,262

WRITING INSTRUMENT

Robert Wright Schier, Northbrook, Ill., assignor to The Parker Pen Company, Janesville, Wis., a corporation of Wisconsin

Filed Oct. 27, 1959, Ser. No. 58,088

Term of patent 14 years

(Cl. D74—17)

Fig. 1 is a side elevational view of a writing instrument showing my new design;

Fig. 2 is a front elevational view thereof on larger scale and with a portion removed for convenience of illustration;

Fig. 3 is a side elevational view thereof showing the side opposite to that shown in Fig. 1;

Fig. 4 is a rear elevational view thereof;

Fig. 5 is a top plan view of the writing instrument shown in Fig. 1 looking in the direction of the arrows 5—5 of Fig. 1; and

Fig. 6 is a bottom plan view thereof looking in the direction of the arrows 6—6 of Fig. 1.

I claim:

The ornamental design for a writing instrument, as shown and described.
